CLAIM

The ornamental design of a gunner protection turret enclosure with adjustable forward gun shield and vehicle adapter plate, as shown and described.

DESCRIPTION

The invention described herein may be manufactured, used, and licensed by or for the U.S. Government for U.S. Government purposes.

FIG. 1 is a front right perspective view of a gunner protection turret enclosure with adjustable forward gun shield and vehicle adapter plate.

FIG. 2 is a front left perspective view of a gunner protection turret enclosure with adjustable forward gun shield and vehicle adapter plate.

FIG. 3 is front elevational view of a gunner protection turret enclosure with adjustable forward gun shield and vehicle adapter plate.

FIG. 4 is a right side elevational view of a gunner protection turret enclosure with adjustable forward gun shield and vehicle adapter plate.

FIG. 5 is a left side elevational view of a gunner protection turret enclosure with adjustable forward gun shield and vehicle adapter plate.

FIG. 6 is a back elevational view of a gunner protection turret enclosure with adjustable forward gun shield and vehicle adapter plate; and,

FIG. 7 is a top plan view of a gunner protection turret enclosure with adjustable forward gun shield and vehicle adapter plate.

The broken lines shown in the Figures depict unclaimed subject matter only and form no part of the claimed design.
